[57] CLAIM

The ornamental design for a grass cutter device, as shown and described.

DESCRIPTION

FIG. 1 is a left side elevational view of the grass cutter showing my new design;

FIG. 2 is a right side elevational view of the grass cutter shown in FIG. 1;

FIG. 3 is a top plan view of the grass cutter as shown in FIG. 1;

FIG. 4 is a bottom plan view of the grass cutter as shown in FIG. 2;

FIG. 5 is a front elevational view on an enlarged scale of the grass cutter shown in FIG. 1;

FIG. 6 is a rear elevational view on an enlarged scale of the grass cutter shown in FIG. 1;

FIG. 7 is a left side elevational view of second modified embodiment of the grass cutter illustrated in FIG. 1;

FIG. 8 is a front elevational view on an enlarged scale of the grass cutter shown in FIG. 7; and

FIG. 9 is a rear elevational view on an enlarged scale of the grass cutter shown in FIG. 7.
